UNITED STATES PATENT OFFICE.

JOHN C. SCHWEIZER, OF TRENTON, NEW JERSEY.

COMBINED SCRUBBER, MOP, AND WRINGER.

949,664.

Specification of Letters Patent. Patented Feb. 15, 1910.

Application filed December 31, 1908. Serial No. 470,237.

To all whom it may concern:

Be it known that I, JOHN C. SCHWEIZER, a citizen of the United States, residing at Trenton, in the county of Mercer and State 5 of New Jersey, have invented certain new and useful Improvements in Combined Scrubbers, Mops, and Wringers; and I do hereby declare the following to be a full, clear, and exact description of the invention, 10 such as will enable others skilled in the art to which it appertains to make and use the same.

The object of my invention is to provide a simple, durable and efficient scrubbing device, 15 comprising a scrubbing-brush, a mop-cloth associated therewith, the brush being adapted to be used alone, when the mop-cloth is turned back into inoperative position, and serving as a resilient backing or 20 abutment for the mop-cloth, when the latter is in use; a pair of wringer rolls through which the mop-cloth is drawn to express the water therefrom, and a pair of drainer-boards located below the rolls which serve to 25 drain away the water expressed from the mop-cloth by the rolls, and to detach from the face of the mop-cloth any solid matter adhering thereto before the cloth passes through the rolls.

30 In the accompanying drawings Figure 1 is a side elevation of my improved device; and Fig. 2 is a plan view thereof.

Referring to the drawings, 1 indicates a yoke, to which is secured a handle, 2, by any 35 suitable means. Rigidly attached to the forward end of said yoke, 1, is a scrubbing brush, 19, which may be of the usual and well known type.

Journalized in longitudinal slots, 7, in the 40 side of the yoke, 1, is a roller, 3, having its surface roughened as by means of longitudinal flutes or grooves, said roller being provided with a crank, 4, by which means the roller may be rotated. Said crank, 4, is conveniently jointed as at 4¹ as to be permitted 45 to be swung backward and downward over the yoke so as to be out of the way when the device is in use. A second roller, 5, is journalized in yoke, 1, in generally parallel relation with roller 3, the ends of the pins or shafts on which said rollers, 3, and 5, are mounted being connected with springs, 6, which tend to move the roller, 3, toward roller 5, and exert considerable pressure 50 upon a looped or continuous mop-cloth, 8, which passes over the brush, 19, and roller 55

5, and between said rollers 3 and 5. As will be apparent from an inspection of the drawings, the slots 7 which form the bearings for roller 3, permit the latter to move toward 60 and from the roller 5, thereby exerting a continuous pressure on the mop-cloth, and also allowing the roller, 3, to yield to accommodate any variation in the thickness of the 65 mop-cloth.

To the sides of the yoke, 1, are secured two pendent brackets, 10, to which are attached two spaced drainer boards, 9 and 11, lying below the rollers 5 and 3 respectively. Board 9 is preferably rigidly attached to 70 brackets 10, and also to the brush 19 so that said board 9 is relatively fixed, while board 11 is connected to brackets 10 by means of screws, 12, which engage elongated inclined slots, 13, in the lower edges of the brackets 75 10, to permit a movement of said board 11 toward and from board 9. The rear end of the board 11 is supported by a flat spring 14, which is attached to yoke 1, and which spring normally tends to force the board 11 80 toward the board 9, so that the rounded or tapered rear edge of board 9 and forward edge of board 11 contact with the surfaces of the mop-cloth 8.

From the foregoing description it will be 85 apparent that when it is desired to use brush 19 for scrubbing, it is only necessary to turn the looped mop-cloth, 8, sidewise and backward over the yoke, to free the brush, which may then be employed in the 90 usual manner, the mop-cloth being retained in the position mentioned by turning back upon it the jointed crank 4. When it is desired to use the mop, the mop cloth 8 is thrown over the brush as illustrated in the 95 drawings, when the face of the brush, 19, serves as a backing or abutment against which the mop-cloth lies when the same is drawn backward and forward over the surface to be mopped or dried. The mop-cloth being supported against the ends of the bristles or fibers of the brush receives therefrom a resilient support, which I find preferable to a rigid support which would be furnished by a hard wood or metal back- 100 ing. When it is desired to expel the water absorbed by the mop, handle 4 is moved into vertical position, as indicated in the drawings, and rotated, thereby drawing the loop of the mop-cloth between boards 9 and 11, 105 which serve the double function of scraping off of the mop any solid matter adhering to 110

either face of the cloth, and also to drain away from the mop-cloth the water expressed from the same by the action of the rollers. After the mop-cloth has been sufficiently freed of water, rotation of roller 3 is suspended and handle 4 turned backward on its hinge 4¹, to a position above the yoke 1, and roller, 3, and the scrubbing and mopping operations may be repeated.

10 I have illustrated the drainer boards, 9 and 11, so inclined as to catch and deflect from their outer sides the water expressed from the mop-cloth by the rollers 3 and 5, but it is obvious that a somewhat different 15 arrangement of these drainer boards will come within the scope of the invention.

Having thus described my invention I claim,—

1. In a scrubbing device, the combination 20 of a handle, a brush carried thereby, and an endless mop cloth looped about the brush.

2. In a scrubbing device, the combination 25 of a handle, a brush carried thereby, and an endless mop cloth looped about the brush but movable to one side of the brush so that the latter may be used for scrubbing.

3. In a scrubbing device, the combination

with a mop cloth, and wringer mechanism, of drainer boards which abut against the mop cloth at opposite surfaces.

4. In a scrubbing device the combination 30 of a mop cloth, wringer mechanism, a fixed drainer board at one side of the mop cloth, and a movable spring-pressed drainer board at the other side of the mop cloth and pressing the same against the fixed drainer board.

5. In a scrubbing device, the combination 40 of a yoke, wringer rollers journaled in said yoke, a mop cloth passing between said rollers, and drainer boards carried by the yoke beneath the wringer rollers and co-acting with the mop cloth at opposite surfaces.

6. In a scrubbing device, the combination 45 of a yoke, flat inclined drainer boards carried by the yoke, wringer mechanism, and a mop cloth acted on by the wringer mechanism and passing between the drainer boards.

In testimony whereof I affix my signature, in presence of two witnesses.

JOHN C. SCHWEIZER.
